SHUTTLE

Sherwood O. Dodge, Medford, Mass., assignor to
Guaranteed Parts, Inc., Allston, Mass., a corporation of Massachusetts

Application October 14, 1936, Serial No. 105,562

1 Claim. (Cl. 139—222)

This invention relates to shuttles and particularly to a thread eye for an automatic self-threading shuttle of the type used in automatic looms.

The object of the invention is to provide a simple inexpensive thread eye for a shuttle, said eye being so constructed and associated with the threading slots of said shuttle that the thread will enter the eye automatically on the second pick and thereafter remain securely threaded in said eye during the operation of the shuttle.

Another object of the invention is to provide a thread eye constructed of a single piece of metal or other suitable material, said eye being inserted in a shuttle without weakening the structure thereof, and being easily replaceable therein if necessary.

The invention consists in a shuttle and thread eye therefor as set forth in the following specification and particularly as pointed out in the claim thereof.

Referring to the drawing:

Fig. 1 is a plan view of an end portion of a shuttle embodying my invention, showing the thread from a bobbin carried by the shuttle threaded through the eye thereof.

Fig. 2 is a side elevation of the same end of the shuttle illustrated in Fig. 1.

Fig. 3 is a longitudinal horizontal section taken on the line 3—3 of Fig. 2.

Fig. 4 is an enlarged top plan view of the thread eye removed from the shuttle and including a thread extending through the thread passage of said eye.

Fig. 5 is a rear or inner end view of the thread eye.

Fig. 6 is a front or outer end view of the thread eye.

Fig. 7 is an enlarged top plan view of another form of thread eye embodying my invention.

Fig. 8 is a front or outer end view of the thread eye shown in Fig. 7.

Fig. 9 is an enlarged top plan view of still another form of thread eye embodying the invention.

Fig. 10 is a front or outer end view of the thread eye shown in Fig. 9.

Like numerals refer to like parts throughout the several views of the drawing.

In the drawing, referring particularly to Figs. 1 to 6 inclusive, 11 represents a shuttle and 12 is a bobbin mounted in a bobbin chamber 13 of said shuttle and having a filling thread 14 wound thereon, all in a manner well known to those skilled in the art. Formed in the upper surface

thread slot 16 which extends from the end of the bobbin chamber 13 lengthwise through said end portion at a slight angle to the longitudinal median line of the shuttle, finally emerging at a side of the shuttle adjacent to a tip 17 thereof. 5

The vertical thread slot 16 flares outwardly at its inner end at 18 where it communicates with the bobbin chamber 13, and the outer end portion of said slot communicates with a horizontal thread slot 19 which extends inwardly from the 10 side of the shuttle upon which the slot 16 emerges, and intersects slot 16 at the bottom thereof. At its rear end the slot 19 terminates in a square hole 20 which is provided in the side of the shuttle 11 for the purpose of receiving a rectangular thread eye 21 illustrated in detail in Figs. 4, 5 and 6, and through which the thread 14 may be threaded automatically or manually as may be desired. The upper surface of the hole 20 and upper surface of the thread slot 19 are 20 coincidental.

The thread eye 21 is approximately square in cross-sectional contour, and is constructed of a single piece of metal or other suitable material commonly used for such purposes, and has a 25 cylindrical thread passage 22 extending longitudinally therethrough. At its inner or rear end the thread eye 21 is provided with a flange 23 above which the filling thread 14 passes while being threaded into the passage 22 of the eye 21. 30 The thread 14 enters the thread passage 22 of the eye 21 from the thread slot 19 through another thread slot 24 formed in the upper portion of said eye above the passage 22, and said slot extends lengthwise of said eye and at a 35 slight angle to the axis thereof, and is diagonally located with respect to the passage 22, and separates the upper portion of the eye into oppositely projecting overhanging and overlapping arched portions 25 and 26 for the passage 22, said overhanging portions overlying the thread 14 which, when threaded into said eye, extends through the passage 22 thereof, as illustrated in Fig. 4, thereby acting to effectively confine said thread in said passage. 45

The upper surface of the overhanging portion 25 forms a continuation of the upper surface of the thread slot 19 and the upper surface of the overhanging portion 26 forms a continuation of the bottom surface of the slot 19, and the slot 24, 50 therefore, forms a downwardly extending continuation of said slot 19. Preferably the opposite side walls of the slot 24 are inclined to facilitate the transfer of the thread 14 from the slot 19 into the slot 24 and into the passage 22, and a side 55

wall 27 of said slot 24 projects above the opposite side wall of said slot thereby forming a shoulder at the top of the thread eye 21 and at the entrance to the slot 24, which causes the thread 14 to be deflected from the horizontal thread slot 19 downwardly into the inclined slot 24. The thread eye 21 is secured in the shuttle 11 by a pin 28 which extends through the shuttle into the flange 23 of said eye.

10 In the operation of an automatic loom, in threading the thread 14 into the eye 21, on the first pick, the thread in unwinding from the bobbin 12, drops into the vertical slot 16 in the shuttle and on the second pick is carried from said slot 15 16 through the slots 19 and 24 into the thread passage 22 where it will thereafter be confined in an effective manner by the oppositely projecting overhanging and overlapping portions 25 and 26 of the thread eye.

20 In Figs. 7 and 8 I have illustrated a modified embodiment of my invention, in which a thread eye 29 is formed of a single piece of suitable material which is hexagonal in cross-sectional contour and has a cylindrical thread passage 30 extending longitudinally therethrough upon the axis thereof. A thread slot 31 provided with inclined side walls communicates with the upper portion of the passage 30 and is positioned diagonally with respect thereto, and said slot 31 separates the upper portion of the thread eye 29 into oppositely projecting overhanging and overlapping portions 32 and 33 for said passage, said portions overlying a thread within the passage and thereby confining said thread therein.

35 In Figs. 9 and 10 still another embodiment of my invention is illustrated in which a thread eye 34 is formed of a single piece of suitable material which is circular in cross-sectional contour and has a cylindrical thread passage 35 extending longitudinally therethrough upon the axis thereof.

A thread slot 36 provided with inclined side walls communicates with the upper portion of the passage 35 and is positioned diagonally with respect thereto, and said slot 36 separates the upper portion of the thread eye 34 into oppositely projecting overhanging and overlapping portions 37 and 38 for said passage, said portions overlying a thread within the passage and thereby confining said thread therein. 5

All of the various embodiments of the invention 10 are similar in every respect except as to their cross-sectional contour, and all of the structures illustrated function in exactly the same manner and are equally effective in maintaining a thread therein. The various forms of thread eyes are 15 each constructed of a single piece of material and are of very simple and rugged construction, and, furthermore, said eyes may be easily inserted in the body member of the shuttle without weakening the structure thereof, and any tendency 20 therefore, for the shuttle to break while doffing the bobbin is reduced to a minimum.

I claim:

In a shuttle, a thread eye having an axial thread passage extending therethrough and also 25 having a thread slot communicating with said passage at the top thereof, said slot extending in a continuous straight line lengthwise of said eye and diagonally with respect to said passage and separating the portion of the eye above the passage into oppositely projecting overhanging and overlapping portions at each end of the passage adapted to confine a thread in the passage, one of the side walls of the thread slot being higher than the opposite side wall, thereby providing a 30 shoulder at the top of the eye and at the entrance to the thread slot, whereby a thread will be deflected into said slot. 35

SHERWOOD O. DODGE. 40
